WITCH'S HAT

Nicholas Veltro, 1183 Elmwood Ave.,
Buffalo, N.Y. 14222

Filed Feb. 12, 1973, Ser. No. 331,889

Term of patent 14 years

Int. Cl. D2—03

U.S. Cl. D2—257

FIG. 1.

FIG. 2.

FIG. 3.

FIG. 4.

FIG. 1 is a top plan view of a witch's hat showing my new design;

FIG. 2 is a rear view of the hat taken from the left-hand side of FIG. 1;

FIG. 3 is a front view of the hat taken from the right-hand side of FIG. 1; and

FIG. 4 is a side view taken from the lower side of FIG. 1.

I claim:

The ornamental design for a witch's hat, substantially as shown.
